UNITED STATES PATENT OFFICE.

FRANK ROMMEL, OF BANGOR, WISCONSIN.

ADJUSTABLE PARTITION OR GATE.

Application filed July 16, 1926. Serial No. 122,962.

The present invention relates to adjustable partitions or gates, and the primary object of the invention is to provide an improved partition or gate construction whereby in-
5 closures of various characters may be partitioned off into various sized compartments.

A further object of the invention is to provide an improved adjustable partition construction embodying novel features whereby
10 the partition forming section may be swung horizontally from either vertical edge thereof in the manner of a gate.

A further object of the invention resides in the provision of an improved partition construction especially well adapted for use in connection with railroad stock and merchandise cars, for providing partitioned compartments of various sizes to meet the requirements of separating live stock shipments, 15 merchandise, machinery, or other articles in transit.

A still further object of the invention is to provide a partitioning means for enclosures which is simple and durable in construction, 20 and which may be readily associated with in-
closures of various descriptions for providing compartments of any desired size.

Other objects and advantages of the invention will be apparent during the course of the
30 following detailed description, taken in connection with the accompanying drawings, forming a part of this specification, and in which drawings,

Figure 1 is a vertical central longitudinal section through one end of a conventional type of stock car, and showing the improved partitioning means associated therewith for providing a compartment of a desired area.

Figure 2 is an enlarged fragmentary view
40 illustrating the manner in which the supporting brackets for the partitions or gates are connected with the guide tracks which support the partitions or gates.

Figure 3 is a detailed view of one of the retaining pins for the supporting brackets.

Figure 4 is a vertical transverse section thru the car on line 4—4 of Figure 1 and looking in the direction of the arrows.

Figure 5 is a detailed sectional view taken
50 on line 5—5 of Figure 2.

Figure 6 is a perspective view of one of the supporting brackets for the gate or partition.

Figure 7 is a plan view of one of the guide
55 tracks for adjustable supporting of the partitions or gates.

Referring to the drawings in detail, and wherein similar reference characters designate corresponding parts throughout the several views, the letter A designates a conventional type of stock car, provided with the improved partitioning means embodying supporting guide tracks B, a partition or gate C, and means D for slidably and adjustably supporting of the member C upon the guide 60 tracks B.

Referring to the car A, and which is of usual and well known construction, the same embodies a roof 10, a floor 11, an end wall 12, and parallel side walls 13 in the example shown composed of a plurality of longitudinally extending horizontal slats 14. These side walls 13 and end wall 12, provide a walled inclosure adapted to be divided into various size compartments by means of a partition or gate C.

The supporting guide tracks B, and four of which are provided for supporting of the partition or gate C, are preferably formed of metal of T-shape in cross section, and of a length equal to the length of the side walls 13. These guide tracks B are disposed in pairs of two at the inner side of each of the side walls 13, for providing upper and lower guide tracks 15 and 16 respectively at the inner side of each of the walls 13. Each pair of tracks 15 and 16, and which extend horizontally and in parallel relation to one another, have their vertically disposed flanges 17 secured to the inner face of one of the side slats 14 as by means of bolts or other suitable fastening elements 18. The horizontally disposed stem portions 19 of the guide tracks, which as will be observed extend inwardly from the side walls 13, are provided throughout 90 their length with a plurality of spaced apertures 20. As will be observed in Figure 4, the stems 19 of the upper guide tracks 15 align horizontally, and the stem portions 19 of the lower guide tracks 16, also align horizontally.

Referring now to the partition or gate C, which is intended for the forming of various sized compartments within the car A, the same embodies the vertically disposed uprights 21 connected by means of a plurality of horizontally disposed rails 22. The uprights 21 are preferably connected at the terminals of the rails 22, and the width of the partition or gate is preferably slightly less than the distance between the confronting edges of the stems 19 of the guide tracks B.

The specific construction of the partition or gate C may be varied in accordance with the specific construction desired, the construction shown merely illustrating one manner in which the partition or gate may be constructed.

Referring now to the means D for adjustably and hingedly supporting the structure C, the same embodies four supporting brackets 25 adapted to be secured to one face of the construction C with the brackets adapted to cooperate one with each of the four guide tracks B. These supporting brackets 25 which are preferably formed of metal, are of L-shape in formation, providing a main body portion 26 having a right angularly extending arm 27 formed at one end thereof. The arm 27 is bifurcated as by a slot 28 for providing upper and lower plates 29 and 30 respectively. This slot 28, and which extends longitudinally of the arm 27, extends for a slight distance into the outer end of the main body portion 26, as at 31. Vertically aligning apertures 32 are provided in the ends of the plates 29 and 30, and these apertures are preferably of a diameter equal to the diameter of the apertures 20 provided in the stem portion of each of the guide tracks B. The main body portion 26 which is preferably of greater length than the arm 27, is provided with spaced apart elongated apertures 33 through which suitable fastening elements or bolts 34 extend for rigidly connecting the supporting brackets to one face of the partition or gate C. As will be observed in Figures 2 and 5, the supporting brackets 25 are secured horizontally upon the partition or gate C with the arm 27 and the inner end 31 of the slot 28 disposed past the end edge 35 of the partition or gate. The upper set of the brackets 25 are adapted to have their bifurcated arm sections 27 engage the upper set of guide tracks 15, while the lower pair of supporting brackets are adapted to have their bifurcated arm portions 27 embrace the stems of the lower set of guide tracks 16. By so providing the apertures 33 of elongated formation, my device will permit slight longitudinal adjustment of the supporting brackets for bringing the aligning apertures 32 into alignment with the apertures 20 provided in the stems of the guide tracks. This feature will also permit slight spreading of the side walls of the car when in transit.

It is preferred that the slot 28 be of a width equal to the thickness of the stem 19 of the guide tracks, in order that when the brackets are connected with the guide tracks, the plates 29 and 30 of the arm 27 will respectively bear upon the upper and lower surfaces of the stem portion 19.

Upon aligning of the apertures 32 of the supporting brackets 25, with the desired apertures 20 of the guide tracks B, retaining pins 40 provided with enlarged apertured heads

41, may be passed vertically downwardly through the aligning apertures 20 and 32, for retaining of the partition or gate C in its adjusted position along the guide tracks B. A suitable chain 42 may be connected at one end with the apertured eye 41 and have its opposite end connected with the partition or gate C for preventing the pin 40 from becoming lost or misplaced.

It will readily be seen how the partition or gate C may be adjusted longitudinally along the guide tracks B for the providing of various sized compartments within a walled enclosure.

Upon removal of the two retaining pins at either end of the structure C, it will be observed that the remaining pins will serve as a hinge pin for permitting of the structure C being swung horizontally in the manner of a gate against one side wall of the inclosure. This hingedly connecting of the structure C, in a manner for permitting the structure to be hingedly hung at either side wall of the car at adjusted positions along the wall, will be found very desirable in meeting the requirements of separating live stock shipments, since such will permit of the stock being first driven into the desired compartments, and then the structure C swung in the manner of a gate and secured by means of the retaining pins 40 for closing of the compartment.

It will of course be apparent that one or more of the partitions or gates C may be supported along the supporting guide tracks B, for dividing the walled inclosure into a number of separate compartments of a desired size.

From the foregoing description it will be apparent that a novel type of partitioning means has been provided for use in connection with railroad stock and merchandise cars, or for use in providing movable partitions in any compartment where it becomes necessary to provide partitions spaced to meet the requirements of separating live stock shipments or merchandise, machinery, or other articles in transit or in storage.

Changes in detail may be made to the specific form of invention herein shown and described, without departing from the spirit of the invention or the scope of the following claims.

I claim:

1. In a compartment forming device for inclosures embodying a pair of parallel spaced apart side walls, the combination of supporting guides mounted horizontally upon the confronting faces of the side walls, said supporting guides being of T shape in cross section and mounted with their stem portions extending inwardly from the side walls, a partition, L-shaped supporting brackets carried by the partition and adjustable longitudinally of the partition, and means car-

ried by the partition for adjustably and hingedly connecting the supporting brackets to the inwardly extending stem portions of said guides.

- 5 2. In a compartment forming device for inclosures embodying a pair of parallel spaced apart side walls, the combination of supporting guides of T shape in cross section mounted horizontally at the confronting faces 10 of the side walls, a partition, supporting brackets mounted at each end of the partition and embodying right angularly extending arm portions offset out of the plane of the partition for sliding engagement with the 15 stem portions of said T shaped guides, and means for detachably connecting the supporting brackets at the ends of said arm portions in adjusted positions along said guides.
- 20 3. In a compartment forming device for inclosures embodying a pair of parallel spaced apart side walls, the combination of

supporting guides mounted horizontally at the confronting faces of the side walls, said supporting guides being of T shape in 25 cross section and having their inwardly extending stem portions provided with a plurality of spaced apart apertures, a partition, supporting brackets carried by the partition and having bifurcated arm portions projecting past the ends of the partition and offset to one side thereof, said bifurcated arm portions forming spaced plates slidably receiving the stem of said guides, and said plates at the terminal of their offset portions being provided with aligning apertures, and a retaining pin carried by the partition at each supporting bracket adapted to extend through the apertures in said arm and an aligning aperture in said stem portion, 40 for adjustably and hingedly connecting said partition at each end to said supporting guides.

FRANK ROMMEL.
